UNITED STATES PATENT OFFICE.

JOHN McLELLAN, OF PROVIDENCE, RHODE ISLAND, ASSIGNOR, BY MESNE ASSIGNMENTS, TO MULTIPLE DRILLING MACHINE COMPANY, A CORPORATION OF RHODE ISLAND.

MULTIPLE-DRILL MACHINE.

Application filed August 4, 1921. Serial No. 489,663.

To all whom it may concern:

Be it known that I, JOHN McLELLAN, citizen of the United States, residing at Providence, in the county of Providence and State 5 of Rhode Island, have invented certain new and useful Improvements in Multiple-Drill Machines, of which the following is a specification.

My invention relates to machines of this 10 type adapted for drilling holes in articles of various materials for any desired purpose wherein a plurality or series of holes in either alignment or parallelism are convenient. The present invention is an 15 improvement of the United States Patent No. 1,075,588 issued to me October 14, 1913.

The essential objects of my present invention are to render the drill driving plate accessible, whereby the entire machine need 20 not be dismantled to remove the plate; to facilitate substitution of drill driving and holding plates of various sizes and forms; to accommodate the machine to the reception 25 of drills disposed in a multiple series, or any other desired convenient arrangement; to enable accurate adjustment of the drill holder blocks relatively to the driving plate; to enable a rapid and accurate initial positioning of the driving plate; to prevent 30 accidental cramping of the driving plate; and to attain these and other ends, which will occur to those versed in the art, in a smoothly operating and inexpensive structure.

35 To the above ends essentially my invention consists in such parts and in such combinations of parts as fall within the scope of the appended claim.

In the accompanying drawings which 40 form a part of this specification,

Figure 1 is a front elevation of machine embodying my invention,

Figure 2, a longitudinal vertical section on line 2—2 of Figure 1,

45 Figures 3 and 4, transverse sections of the same on lines 3—3 and 4—4 respectively of Figure 2,

Figure 5, a section on line 5—5 of Figure 1, and

50 Figure 6, a front elevation, partially in vertical section, of the drill holder blocks.

Like reference characters indicate like parts throughout the views.

The framework of my machine may be of

any construction adapted to conveniently 55 carry the operating mechanism. In the form thereof herein shown it includes a base 10, a standard 11 upon its rear end, an intermediate support 12, and, upon its forward end a transversely disposed support 60 13 provided with lateral uprights 14 and a cross piece 15 connected to the latter by bolts 16.

In detail the support 12 has in this instance a base portion 17 and a circular upper 65 portion 19 provided with a cylindrical bore 20 which constitutes an annular supporting portion. A constituent part of this support is a detachable circular face plate 22 provided with a central opening 23, and having 70 an annular boss 24 together with a marginal annular flange 25 upon its rear face. The latter is a sliding fit in the bore 20. The plate is engaged with the annulus 19 by a circular series of screws 27 passing through 75 holes 28 in the face plate and engaging in threaded holes 29 in annulus.

Fast in the standard 11 is a spindle or horizontal shaft 32 upon which is revolvably mounted a pulley 33 comprising a hub 34, a 80 body or web 35 and a rim 36. The exterior end portion of the rim slidably engages the flange 25, and an annular shoulder 37 abuts against the end of the latter.

Fast to the reduced end of the spindle 32 85 is a recessed thrust disk 40 held by a nut 41. The disk and adjustable collar 43 cooperate to prevent endwise movement of the pulley. A second adjustable collar 45 upon the disk in this instance abuts against the standard 90 11. Integral with the inner face of the pulley rim 36, or fastened thereto in any convenient manner is a flange or disk 47 provided with an eccentric bore 48. Slidably mounted in flange 47 is a circular driving 95 disk 50 with side faces in slidable contact with the abutment 24 and end thrust disk 40. Integral with the center of the member 50 is a cylindrical boss 52 extending through the opening 23 of the attaching plate. Detachably mounted upon the end of the boss 100 is a driving plate 54, preferably disk shaped, which has a centrally disposed stud 56 upon its rear face provided with a thread 57 adapted to engage a thread 58 in an axial 105 recess 59. The threaded socket 59 is slightly deeper than the length of the boss to insure a tight frictional contact of the plate 54

with the boss. The latter is provided with a slot 61 to accommodate a wrench for facilitating detachment of the two driving members. The plate is provided with a diametrically disposed series of holes 62 to loosely receive the inner ends of the drills 63, each of which comprise a straight body or operating portion 64, an inclined intermediate portion 65, bent at an angle to correspond with the eccentricity of the flange 48, and an offset end portion 66 registering in one of the holes.

A sectional drill holder 69 is provided of any preferred shape. In this case it comprises a pair of blocks 70, each of whose contiguous faces 71 is provided with parallel longitudinally disposed slots 73, and with a series of transversely disposed semi-circular registering holes 75. The portions 64 of the drills are rotatably mounted in these holes, and collars 77 fast to said portions and in staggered relation to each other, are loose in the slots 73. With the drills thus arranged the blocks are clamped together by means of bolts 79.

The described holder is vertically and horizontally adjustable in guide flanges 81 fast to the upright 14 of the frame, and rests upon spacing plates 83 placed on the support 13 with their ends between flanges. Vertically disposed clamping screws 85 threaded in the cross piece 15 engage the top of the holder 69, and horizontally disposed adjusting screws 87 threaded in the uprights engage the lateral sides thereof.

The machine is operated as follows: The pulley 33 is driven by a belt or otherwise from any convenient source of power, and through the eccentric flange 47 moves the disk 50 bodily in a circular path in varying parallel horizontal planes, and without any revolution of the disk upon its own center. The degree of eccentricity of the flange 47 corresponds with the angle of inclination of the intermediate portions of the drills. The movement of the member 50 is imparted through the members 52 and 56 to the plate 54, which in turn rotates the drills 62 in

unison. If desired the members 52 and 56 may be insured against cramping or strain occasioned by any accidental tilting or rotary movement of either of them by providing diametrically oppositely disposed perforated projections 89 upon the periphery of the member 54 in which are engaged the upper ends of helical springs 91 whose lower ends are engaged in perforated projections 93 on the base 10.

This construction lends itself to the facile substitution of driving plates 54 of various diameters, and with differing numbers of drill holding sockets and series of sockets, and with sockets otherwise arranged. To correspond with such substitutions the number of holders 69 may be increased or other holders may be substituted or the holders may be adjusted in any desired direction, by adding or removing some of the plates 83 or turning the screws 85 or 87. It will be understood that to facilitate any substitution the cross piece 15 may be removed by loosening the bolts 16.

I claim:

In a multiple spindle drilling machine, a base, an annular support, a retaining plate upon the support provided with a central orifice, a standard on the base, a spindle on the standard, a pulley on the spindle extending within the annular support and provided with an eccentric seat, a driving disk loosely mounted in the eccentric seat in slideable contact with the retaining plate, a thrust disk upon the spindle slidably engaging the driving disk, a boss on the driving disk projecting through the orifice, a driving disk detachably mounted on the boss exterior of the retaining plate provided with drill sockets, a tool holder support on the base adjacent the first support, a tool holder upon the second support, and drills comprising bodies rotatably mounted in the holder, and offset ends in the sockets.

In testimony whereof I have affixed my signature.

JOHN McLELLAN.
